CLAIM

I claim the ornamental design for a disposable bag, as shown and described.

DESCRIPTION

FIG. 1 is a front view of a first embodiment of the disposable bag showing my new design;

FIG. 2 is a front view, the rear view being a mirror image thereof;

FIG. 3 is a side view, the other side being a mirror image thereof;

FIG. 4 is a top view thereof;

FIG. 5 is a bottom view thereof; and,

FIG. 6 is a front view of a second embodiment of the disposable bag; the side, top and bottom views of FIG. 6 being identical to the side, top and bottom views of FIG. 1.

1 Claim, 3 Drawing Sheets
